UNITED STATES PATENT OFFICE.

JOSEPH H. LYONS, OF CLEVELAND, OHIO, ASSIGNOR TO THE VICTOR BRASS MANUFACTURING COMPANY, OF CLEVELAND, OHIO, A CORPORATION OF OHIO.

PRIMING DEVICE FOR INTERNAL-COMBUSTION ENGINES.

1,319,350.

Specification of Letters Patent.

Patented Oct. 21, 1919.

Application filed November 26, 1917. Serial No. 203,875.

To all whom it may concern:

Be it known that I, JOSEPH H. LYONS, a citizen of the United States, residing at Cleveland, in the county of Cuyahoga and 5 State of Ohio, have invented a certain new and useful Improvement in Priming Devices for Internal-Combustion Engines, of which the following is a full, clear, and exact description.

10 In many cases it is desirable, and frequently it is necessary, to discharge into the cylinders or the inlet manifold of an internal combustion engine, a quantity of easily vaporized liquid fuel before the engine can be 15 started. In some cases gasolene may be used for this purpose, but generally speaking, it is desirable to use some fluid fuel which vaporizes more readily than gasolene, as for example, alcohol or, preferably, ether.

20 The present invention is a device adapted to be easily attached to the cylinders or inlet manifold of an internal combustion engine, and with which one may easily and without loss discharge into each cylinder or into 25 the manifold a definite quantity of this easily vaporizable fuel.

The invention consists in the construction and combination of parts shown in the drawing and hereinafter described and pointed out definitely in the appended claims.

In the drawing, Figure 1 is an end view of the device; Fig. 2 is a side elevation with the body portion sectioned and the valve partly sectioned; Figs. 3, 4, 5 and 6 are vertical transverse sections through the device showing the valve thereof in various positions; Fig. 7 is a side elevation of the device; Fig. 8 is an end view of the small end of the valve; Fig. 9 is an inside view of the washer, 40 Fig. 10 is an end view of nut 35.

Referring to the parts by reference characters, 10 represents the tubular body of the device, which has its lower end 12 threaded to facilitate its connection with an engine 45 cylinder or manifold. This body is likewise formed at its upper end with a cup 13 for receiving the fuel to be discharged, by means of the device, into said cylinder or manifold. Midway between the ends of this body is a 50 transverse barrel 14, which is internally tapered. The hole 15 in the upper part of

the body and the discharge hole 16 in the lower part of the body connect with the conical bore of this barrel.

20 represents a hollow conical valve which is rotatably fitted within the barrel 14; and it has on its large end an operating handle 21; and is formed on its small end with an axially disposed stem 22, the end 23 of which is threaded. This stem is flattened as shown to fit a hole in the washer 30.

This washer 30 fits against the small end of the barrel and closes it. It is formed with a central sleeve 31, at the inner end of which is an inturned flange 32. The hole within the flange 32 is of such shape that it loosely fits around the flattened stem 22, so that when the valve is turned the washer must also turn. A coil spring 34 is placed within the sleeve 31 in engagement with the flange 32; and a cap nut 35 is screwed onto the end of the stem against this spring thereby putting it under tension, with the result that the washer 30 will be held firmly against the end of the barrel 14, and the valve 20 will be drawn snugly into the conical hole through this barrel, but if the valve should chance to stick in the barrel it might still be drawn endwise to loosen, because the spring 34 will yield sufficiently for this purpose, and the diameter of the nut is such that it may telescope into the washer sleeve 31.

As stated, the valve 20 is hollow, but it has in its walls numerous holes, the location and purpose of which will now be explained. There are first two filling holes 24, 25, which are of such size and so located that when the valve is in the position shown in Figs. 2 and 3, both of these holes will be in communication with the filling hole 15 in the upper part of the body. When the valve is in this position there is no hole through its opposite wall communicating with the discharge hole 16. Through the wall of the valve there is however, a discharge hole 26; and the valve may be turned to the emptying position shown in Fig. 6, whereby the interior of the valve is placed in communication with the discharge hole 16. There are likewise two diametrically opposed holes 27, 28, in the wall of this valve. Therefore when the valve is in the position shown in

Fig. 5 any fluid poured into the cup will pass immediately through the valve to the discharge hole 16.

These various holes are so placed that the 5 valve may be turned to the position as shown in Fig. 4, in which fluid can neither run into or out of the hollow valve.

On the large end of the barrel is a graduation mark 40; and on the large end of the 10 valve are other graduation marks F and E for coöperation with it, so that the operator may know when he has turned the valve to bring it into the desired position. In the small end of the barrel are several V-shaped 15 notches 29; and on the inner face of the washer is a V-shaped lug 39 for engagement with one or the other of said notches. When the operator turns the valve he necessarily turns this washer, and he knows when he 20 has turned the valve to the proper position, by the graduation marks adjacent the handle, and when he has reached the proper position this lug will snap into one of said notches, and hold the valve against accidental 25 placement.

When the valve is in the position shown in Figs. 2 and 3, and ether or other volatile fuel liquid is put in the cup, it will flow into the hollow valve, through one or the 30 other of the holes 24, 25,—while the displaced air will flow out through the other hole. Generally the valve will be put into the position shown in Fig. 4, and the cup filled. Then the valve will be quickly 35 turned to the position shown in Fig. 3. If there be only one of the holes 24, 25, there will be such delay in the flowing of the fuel into the valve, and such a stirring up of said fluid by the escaping air, that a substantial 40 loss of fuel by volatilization will take place before the fuel flows into the valve.

When the fuel is in the valve, it may be carried therein as long as desired, if the valve is in the position shown in Fig. 4. 45 When the valve is turned to the position shown in Fig. 6, this fuel will flow out of the valve and through the hole 16, to the engine.

The end of the nut 35 is formed with a series of ratchet like teeth 35^a on its inner end. The end 39^a of the coil spring 34 is turned up so as to engage these teeth. Therefore the spring, while it will permit the nut to be screwed onto the stem, will act as a lock to 55 prevent said nut from being unscrewed.

Having described my invention, I claim:—

1. In a device of the character specified, the combination of a tubular body having a transversely disposed internally conical 60 barrel which intersects the hole through the body, a conical valve which is rotatably fitted in said barrel and has a stem which projects from its small end out of said barrel, a washer which embraces said stem and may

slide upon it but must turn with it and 65 which engages against the small end of the barrel, said engaging surfaces having the one a V-shaped projection and the other a plurality of notches to which said projection is fitted, a nut which screws onto the 70 end of said stem, and a spring which surrounds said stem and is composed between said collar and nut.

2. In a device of the character specified, the combination of a tubular body having a 75 transversely disposed internally conical barrel which intersects the hole through the body, a conical valve which is rotatably fitted in said barrel and has a flattened stem which projects from its small end out of 80 said barrel, a washer which loosely embraces said flattened stem and engages against the small end of the barrel and has a central sleeve at the inner end of which is an in-turned flange, a coil spring within said 85 sleeve around said stem engaging said in-turned flange, and a nut which screws onto the end of the stem and bears against the spring and is of such diameter that it may telescope within said sleeve. 90

3. In a device of the character specified, the combination of a tubular body having a transversely disposed internally conical barrel which intersects the hole through the body, a conical valve which is rotatably fitted 95 in said barrel and has a flattened stem which projects from its small end out of said barrel, a washer which loosely embraces said flattened stem and engages against the small end of the barrel and has a central sleeve at the inner end of which is an in-turned flange, a coil spring within said 100 sleeve around said stem engaging said in-turned flange, and a nut which screws onto the end of the stem and bears against the spring and is of such diameter that it may telescope within said sleeve, said nut having a serrated inner end, and said spring having an outwardly bent end which engages the serrations in the end of the nut. 105

4. In a device of the character specified, the combination of a tubular body having a transversely disposed internally conical barrel which intersects the hole through the body, a hollow conical valve which is rotatably mounted in said barrel, resilient means for holding the valve to its seat, said valve having four holes through its walls two arranged at diametrically opposite points and the other two being arranged at nondiametrical points and graduation marks on the large end of the barrel and on the large end of the plug valve to show when the various holes are in operative positions. 115

5. In a device of the character specified, 120 the combination of a tubular body having a transversely disposed internally conical barrel which intersects the hole through the

body, a hollow conical valve which is rotatably mounted in said barrel, resilient means for holding the valve to its seat, said valve having four holes through its walls two arranged at diametrically opposite points and the other two being arranged at nondiametrical points and graduation marks on the large end of the barrel and on the large end of

the plug valve to show when the various holes are in operative positions the upper 10 end of said body being in the form of an open top priming cup.

In testimony whereof, I hereunto affix my signature.

JOSEPH H. LYONS.
